M. E. COX

AIR COOLED SEAT CUSHION FOR AUTOMOBILES

Filed April 19, 1923

Inventor:
M. E. COX,
W. Anderson,
Atty.

UNITED STATES PATENT OFFICE.

MARY ELIZABETH COX, OF BEAUMONT, TEXAS.

AIR-COOLED SEAT CUSHION FOR AUTOMOBILES.

Application filed April 19, 1923. Serial No. 633,247.

To all whom it may concern:

Be it known that I, MARY ELIZABETH Cox, a citizen of the United States, residing at Beaumont, in the county of Jefferson, State of Texas, have invented certain new and useful Improvements in Air-Cooled Seat Cushions for Automobiles and Other Vehicles, of which the following is a specification.

10 My invention relates to seat cushions designed more particularly for automobiles; and its object is to provide such a cushion in which parts may be readily separated for laundering when becoming soiled, and in 15 which also improved elasticity or resiliency will be afforded, and ventilation provided for, and which is capable of being folded into comparatively compact form when desired.

20 To the accomplishment of the foregoing and such other objects as may hereinafter appear the invention consists in the features hereinafter described and then sought to be clearly defined by the claims, reference 25 being had to the accompanying drawing forming a part hereof, and in which—

Figure 1 is a plan view of the cushion with portions broken away to show some of the interior parts;

30 Figure 2 is a longitudinal section on line 2—2 of Figure 1;

Figure 3 is a cross section on line 3—3 of Figure 1.

In the drawing the cushion is represented

35 as composed of a lower fabric or base 1 and an upper fabric or covering 2, formed of canvas, duck or other suitable material of any desired color, and formed along their margins with suitable snap-fastenings 3 by

40 which one will be attached to the other and permitting easy separation of the cover 2 when to be laundered or to permit access to the interior of the cushion. To the base member 1 are attached in some suitable

45 manner a number of strips 4 of relatively elastic or pliable material, preferably cork, having preferably a thickness of approximately one-half inch, two inches in width, and say eighteen inches in length, spaced

50 preferably about one inch apart, and thus approximately covering the area of the cushion. These cushioning strips give relative firmness to the base member and contribute to some extent to the resiliency and

pliability of the base member. The upper 55 member or covering to the cushion is formed with rows of air vents 5 formed preferably by metal eyelets 6 clinched to the cover so as to afford thorough ventilation and air circulation through the cushion and thus tending to prevent undue warmth to the body of the person resting against the cushion and undue moisture to clothing by reason of perspiration. Between the rows of air vents are placed strips 7, of suitable spring metal, 60 of suitable stiffness to hold the covering in a taut condition without undue sagging, which strips may be suitably attached to the covering fabric, for instance by pockets formed as a part of the covering to receive 70 the same, or otherwise. The ends of the strips are formed with tips 8 of rubber, felt, or other material, that will prevent the ends from cutting or wearing the fabric covering. When the cover is applied and secured 75 to the base member by snap fasteners the metal strips will be confined and prevented from working out of their attaching means, and when the cover is to be laundered the strips can readily be removed. These strips 80 are formed between their ends with hinges 9 which make it possible to fold when desired.

The construction described provides a cushion comparatively light and readily handled, occupying little space, and giving 85 ease and comfort to an occupant of the automobile. The cover can be readily removed for access to the interior and for laundering purposes.

I have described the preferred details of 90 construction but it is obvious that changes can be made in the details and features of the invention retained.

Having described my invention and set forth its merits what I claim is:—

1. A cushion comprising oppositely disposed fabric members having means for detachably attaching one to the other, a plurality of cushioning strips secured to one member, a plurality of spring-metal strips 100 attached to the other member and extending transversely to the cushioning strips, and a series of air vents formed in one of the fabric members.

2. A cushion comprising oppositely disposed fabric members provided with marginally disposed snap fasteners for securing one member to the other, a plurality of

2
pliable stiffening strips secured to one member, rows of eyelet air vents in the other member, and hinged metal strips secured to the member between the rows of eyelet vents.

3. A cushion comprising oppositely disposed separable fabric members, stiffening

strips attached to each of the fabric members, the strips of one member extending transversely to those of the other member, and rows of air vents disposed alongside the stiffening strips attached to the member in which the vents are formed.

MRS. MARY ELIZABETH COX.
